UNITED STATES PATENT OFFICE

WILLIAM LINDSEY, OF CHICAGO, ILLINOIS, ASSIGNOR TO WM. WRIGLEY JR. COMPANY,
OF CHICAGO, ILLINOIS, A CORPORATION OF DELAWARE

WRAPPING MACHINE

Application filed February 11, 1929. Serial No. 338,984.

This invention relates to improvements in wrapping machines, and more particularly to machines for wrapping and packaging sticks of chewing gum.

5 The particular machine to which the herein disclosed improvement pertains, is one such as described in the patents to A. M. Price Nos. 1,109,461 and 1,185,822, to which reference may be had for a more complete disclosure of the construction and operation than is here necessary, since the improvement has to do with the means for carrying out but one step in the wrapping operation, namely, that of applying adhesive at the 10 edges of the wrappers in order to seal them as they are wrapped and folded about the individual sticks.

In general, the operation of a machine to which the present improvement may be applied, is to feed the individual sticks from a vertical magazine or chute into a revolving drum having substantially radial stick receiving slots. The wrappers which are fed from rolls and cut to length, are fed into the 20 path of the sticks as they are delivered edge-wise from the magazine, the wrappers enveloping three sides of the sticks as they are carried thereby into the slots. The continued rotation of the drum completes the 25 folding of the wrapper around the stick, whereupon the folding over of the ends of the wrapper occurs after the delivery of the stick from the drum. Beyond the individual stick wrapping mechanism is suitable mechanism 30 for stacking several sticks into package form, and finally applying a band around each package.

It has been the practice heretofore to wrap the individual sticks but not to seal the wrappers, although it is common practice to enclose the package in a wrapper of paraffine paper which is sealed by heat. The present invention therefore contemplates the complete sealing of each individual stick by the 35 application of glue along the edges of the wrapper just in advance of the wrapping operation. Such a wrapping material is preferably a metal foil (tin or aluminum) with a lining of thin paper.

50 Hence the object of the invention to pro-

vide a glue applying mechanism which will deposit a thin line or streak of glue along the edges of the wrapper so that on completion of the folding operation, the wrapper will be completely sealed about the enclosed 55 stick.

A further object of the invention is to provide a glue applying mechanism which will simultaneously or successively apply thin lines of adhesive along one of the lengthwise edges and both of the end edges of each wrapper, and in such manner that a uniform feed is maintained only during the operation of the machine, thus avoiding waste and excessive flow of the fluid adhesive upon 60 the wrappers. 65

A preferred embodiment of the invention is disclosed in the accompanying drawings, in which

70 Figure 1 is a general view in side elevation of that portion of a wrapping mechanism immediately associated with and including the adhesive applying mechanism.

75 Figure 2 is an enlarged detail view in side elevation showing the adhesive applying mechanism and adjacent wrapping mechanism with portions shown in section.

80 Figure 3 is an enlarged view in front elevation of the wrapping and adhesive applying mechanism of the machine.

85 Figure 4 is a perspective view of the adhesive applying mechanism in one position of the wrapping operation.

Figure 5 is a detail view in vertical section through the glue feeding mechanism for the applying rollers as taken on line 5—5 of Figure 4, but with the reservoir removed.

90 Figure 6 is a detail view in vertical section taken on line 6—6 of Figure 1 showing the mechanism for folding of the end flaps of the wrapped sticks.

95 Figure 7 is a detail view in vertical section taken on line 7—7 of Figure 1 showing the end flaps of a wrapped stick in the process of being folded under to complete the packages.

Figure 8 is a perspective view showing the manner in which the adhesive is applied along the end margins of the wrappers.

100 Figures 9, 10, 11 and 12 are perspective

views showing the successive steps in the wrapping and sealing of a single stick.

Briefly describing the stick and wrapper feeding mechanism, Figure 1, a vertical magazine 1 supports a pile of flat sticks S adapted to be fed edgewise in rapid succession from the bottom of the magazine into peripheral slots in a rotating drum 3 turning on a horizontal axis adjacent the lower end of said magazine. These slots 3a are shown as being four in number and spaced apart at equal intervals about the periphery and so disposed that with each quarter revolution of the drum one of the slots is brought into register with the discharge entrance of the magazine 1. A rocking feed arm 4 moves inwardly and outwardly toward the drum 3 and across the bottom of the magazine 1, and with each reciprocation carries a stick with its wrapper into one of the slots 3a waiting to receive it, as shown in Figure 2. This feed arm is mounted at the upper end of a vertical link 5 connected at its lower end with one end of a horizontal link 6 pivotally connected at its opposite end to a fixed point of the machine frame at 7. The vertical link 5 is connected intermediate its ends and nearer its upper end with an eccentric 8 keyed to a shaft 9 driven at the proper speed to impart the desired forward and return motions to the fed arm 4.

The material from which the wrappers are formed, is fed from a roll (not shown) supported on a spindle mounted on the machine above and to the rear of the magazine 1. This material is preferably a metal foil with an inner coating of thin paper, although any suitable wrapping material may be used which has moisture-proof qualities and surfaces which will seal readily with the use of glue. Near the top of Figure 1, a strand or web W of the wrapping material leads from the roll to a pair of feed rolls 10, 10 mounted near the top of the magazine. These feed rolls are driven by a sprocket wheel 11 mounted on the shaft of one of the rolls and a chain 12 leading downwardly to a sprocket wheel (not shown) but keyed to the driven shaft 9.

A second pair of feed rolls 13, 13 is mounted below the first pair 10, 10 and on the magazine 1, a short distance above its lower end. These rolls are also driven at the same speed as the upper pair and by means of gearing which does not appear. The web W passes between the first pair of rolls 10, 10 and thence to the second pair with an appreciable slack between to prevent undue strain.

Just below the lower set of feed rolls 13, 13 is a cutter consisting of a blade 14 mounted on a rocker arm 14a. The web W passes between said cutting blade and a fixed cutting member 14b, and by the intermittent operation of the cutter, the advancing strip W is cut or severed in rectangular sheets or wrap-

pers w with serrated front and rear edges, as shown in Figure 9.

Continuing downwardly on leaving the cutter, the wrappers w come into contact with a feed roller 15 just above the drum 3, and thence carried between said roller and drum, the latter rotating in a clockwise direction (Figures 1 and 2).

As each wrapper is fed onto the drum, it extends over one of the slots 3a, and as the latter reaches a horizontal position opposite the lower end of the magazine 1, the feed arm 4 advances, forcing a stick S with its wrapper into the slot, as shown in Figure 2. As the drum continues to rotate, the partially wrapped stick is carried around through approximately 180° to a position at the bottom of the drum. During this movement, the leading edge of the wrappers w projects from the slot to be wiped or folded across the entrance of the slot as it encounters a member located in its path. Finally, when the drum has turned through 180°, the stick is ejected from the drum in a horizontal rearward direction, by vertical ejector plates 16, 16 having a circular motion in a vertical plane and provided with recesses 16a which pick up the wrapped stick and deliver it from the drum.

The wrappers are larger than the sticks, so that on being delivered from the drum, each stick is enclosed by a wrapper but the ends of the latter project outwardly in the form of flaps as shown in Figure 11. As the wrapped stick leaves the drum, it is advanced along tracks 17, 17 (Figures 6 and 7) above which are folders 18 which act in cooperation with circularly moving folding blades 19, 19 to fold the end flaps downwardly and inwardly until they are brought against the bottom of the stick as shown in Figure 12. From this point on the wrapped sticks are fed into another drum 20 whereby bands are applied about each, the same being fed to said drum from a magazine 22 and applied to the sticks in much the same manner as were the wrappers fed to the drum 3 and applied to the bare sticks, except that the bands are not folded around the ends of the wrapped sticks.

It is not thought necessary to describe further details of construction or operation of the machine, inasmuch as it is fully described in U. S. Letters Patent No. 1,491,970 to Price, hereinbefore mentioned.

In the preceding description of the wrapping operation, no mention was made of the means for applying the adhesive to the wrappers—the subject matter of the present invention. But with a clear understanding of the wrapping action, the application of the adhesive to the wrappers and mechanism for so doing, will be readily followed, and particularly when it is pointed out that once the glue is applied to the wrappers, the sealing

or adhesion takes place as the wrappers are folded around the sticks.

There are two adhesive-applying devices used, one quite independent of the other. 5 One of these devices applies a thin line of glue along the end edges of the wrappers as they are fed onto the drum 3, and the other device applies a line of glue along the projecting portion or tongue of the wrappers after they have been carried into the slots of 10 the drum by the sticks and before ejection therefrom.

Referring to the first mentioned glue-applying device, the same is associated with the feed roller 15 located above the drum 3. The 15 immediate glue-applying members are thin metal discs 23 mounted on the feed roller 15 (Figure 4) having contact with the drum near each end. As thus located, these discs 20 are spaced a short distance inwardly from the side edges of the wrapper so that in passing between the drum and these discs, a thin line or streak of glue *g* is deposited along the edges of each wrapper (Figure 8) and on 25 what is the inner face thereof after the wrapper is folded around the stick. These lines or streaks *g* are also shown in Figures 4, 9 and 10.

To supply glue to the discs and keep them 30 uniformly saturated, a glue pot or reservoir 24 is mounted at one end of the feed roller 15, and small pipes 25, 25 lead from the reservoir to each of the disc 23, these pipes extending above the discs and provided with 35 downwardly opening nipples 25a close to the peripheries thereof (Figure 4).

It will be observed that the glue pot 24 is 40 below the level of the supply pipe 25 and hence the glue must be elevated in order to reach the inlet end of the pipe from whence it may drain by gravity to the applying discs. This method of supplying the adhesive is preferred to a direct gravity feed from the reservoir, inasmuch as it functions only 45 while the machine is operating.

Referring more in detail to the feed roller 15, the same includes a driven shaft or spindle 26 rotating at the same speed as the drum 3 and in a counterclockwise direction. The end 50 of the shaft 26 at which the glue pot is located, terminates in an integral roller 26a of about twice the diameter of the shaft, and having a boss 26b. Surrounding the roller 26a is a cylindric casing 27 integral with a bearing sleeve 28 in which the end of the shaft 26 is journaled. An opening 29 through the top 55 of this casing connects the space between the piping and the periphery of the roller with the inlet end of the feed pipe 25. The casing opens endwise and has an internally threaded flange 27a extended endwise beyond the disc 26a and which supports the glue pot 24, the latter having an integral threaded collar 24a at one end designed to 60 screw into the threaded flange 27a of the cas-

ing 27. The glue pot is preferably cubical in shape with a filling opening 24b in its top wall. At the inner end of the glue pot is mounted a cylindric block 30 cored out to provide a cavity 30a for the boss 26b of the shaft 70 26. The block terminates short of the bottom wall of the glue pot, thereby forming a relatively small opening or passage 31 through which the glue in the pot can come into contact with the lower portion of the roller 26a. Thus as the roller revolves with the shaft, the glue from the pot is continually carried upwardly filling the space below the outlet opening 29, and thence overflowing into the glue supply line 25, the roller thus 75 acting to elevate the glue to the level of discharge from the casing. The rate of feed is, of course, gauged by the requirements of the applying disc 23, and so long as the machine is in operation, the glue will be supplied. 80 However, should the machine stop temporarily or shut down for long periods, the flow stops instantly inasmuch as any drainage would be back into the glue pot rather than to the applying discs. Hence there is no 85 necessity for valves, or reliance on the promptness of the operator in shutting off or turning on the glue supply at the proper time in order to avoid an excessive feed in the one case, or an insufficient feed in the other. 90

Referring now to the other glue applying device, the same comprises parts as follows: Mounted somewhat forwardly and below the drum 3 is an open trough or glue reservoir 31 (Figures 1, 2 and 4) having upwardly extending end walls or plates 31a providing bearings for the several rotative parts of the device. Above this reservoir is a glue roller 32 mounted on a shaft 32a with its lower portion extending into the reservoir so that it 100 will be partially immersed in the liquid glue supplied thereto. The shaft 32a is driven by a suitable arrangement of driving members (not shown) and rotates in a clockwise direction and about an axis parallel with that of the drum 3. The speed of the roller is relatively slow, being just fast enough to maintain a coating of glue on its surface. 105

Located between the glue roller and the drum is a rotative transfer blade 33 fixed to a shaft 34 parallel with the axes of said drum 3 and roller 32, and positioned substantially midway between the two. As shown in Figures 1 and 3, the shaft 34 is driven from the shaft 32a by means of a pair of meshing gear wheels 35 and 36 keyed to adjacent ends of said shafts 32a and 34, respectively, the latter being slightly smaller so that the transfer blade turns at a slightly greater speed than the glue roller. 115

The transfer blade 33 is a rectangular metal plate extending lengthwise of the drum 3 and divided into two halves or sections extending radially from its supporting shaft 34, the length of the blade sections being 120 125 130

equal to the distance between the shaft and the periphery of the glue roller. Thus as the blade rotates, a quantity of glue is wiped from the surface of the roller as each edge of the blade comes into contact with it. It will be observed, however, that the edges of the blade clear the drum, but are brought into contact with the projecting marginal portions of the wrappers by means of a presser bar 37 mounted in the path of the projecting margins of the wrappers and adjacent the path of the transfer blade (Figures 2 and 4). This presser bar is mounted at one end of a rocker arm 38 which is journalled intermediate its ends on a stub shaft 39 supported by one of the end plates 31a of the glue reservoir, and substantially in the plane of the eccentric 8. The free end of the rocker arm terminates in a trip finger 38a positioned adjacent the path of the eccentric 8, the latter including the usual type of eccentric sheave 8a consisting of a split collar joined together by bolts 8b passing through projecting bosses 8c (Figure 2). Thus as the eccentric rotates, it trips the rocker arm as each trip member (formed by the bosses 8c, 8c) strikes the end of the finger 38a. This tripping action throws the presser bar forwardly through a small arc toward and into the path of the edges of the transfer blade, carrying with it each projecting edge or flap of a wrapper as it is transported downwardly by the drum. The tripping of the presser bar is so timed that it occurs at the instant the wrapper comes into contact with the face of the bar, and likewise when the transfer blade reaches a position opposite the same, and successively presenting its edges to the inner surface of the wrapper. Thus in Figures 2 and 4, the drum has brought a stick with its wrapper opposite the presser bar 37, with the extended margin of the wrapper lying on the face of the bar. The transfer blade is rotating in a counter-clockwise direction with one edge about to reach a position opposite the presser bar. At this instant, the presser bar moves forward with a quick motion bringing the flap momentarily into contact with the edge of the blade and then dropping back to its normal position. By this contact, a strip or streak of glue is transferred from the edge of the blade onto the inner face of the wrapper just inwardly from its outer serrated edge, as shown at g' in Figure 10, and in dotted lines in Figure 4. As each wrapper is presented, a similar movement takes place, each edge of the blade being replenished with glue by wiping across the face of the roller 32, which is constantly turning in the glue supplied to the reservoir.

Having set forth a preferred embodiment of my invention, I claim:

1. In an adhesive-applying device the combination of an adhesive reservoir, a feed roller having its lower portion immersed in the ad-

hesive in said reservoir, a rotative transfer blade having radially disposed edges adapted for wiping contact with the surface of said roller, a presser bar pivotally mounted adjacent the path of the edges of said blade, and tripping mechanism operative to shift said presser bar toward the edges of said blade as the same are rotated into adhesive-applying position. 70

2. In an adhesive-applying device, the combination of a sheet feeding member, an adhesive-applying member adjacent said sheet feeding member and having a transfer blade adapted to be presented edgewise toward the sheets being advanced by said feeding member, a presser bar positioned in the path of said sheets, and means for intermittently oscillating said bar to press the sheets against the edge of the blade of said adhesive-applying member. 75

3. In an adhesive-applying device, the combination of a sheet feeding member, an adhesive-applying member adjacent said sheet feeding member and including a rotative transfer blade adapted to be presented edgewise to the path of successive sheets being advanced by said feeding member, an oscillating presser bar mounted parallel with said blade and on the opposite side of the path of said sheets, and means for intermittently oscillating said presser bar to bring said sheets into contact with the edge of said blade. 80

4. In an adhesive-applying device the combination of a rotative sheet feeding member, an adhesive supply roller below said feeding member, a transfer member intermediate said supply roller and said feeding member, and comprising a blade rotative about an axis parallel with the axes of said roller and feeding member and adapted in its rotation to have wiping contact with said roller and to travel in an arc adjacent the path of the sheets being advanced by said feeding member, a pressure bar mounted in the path of said sheets, and means for intermittently oscillating said bar to carry said sheets into contact with the edge of said blade in its adhesive transfer position. 100

5. In an adhesive-applying device, the combination of a rotative article-holding member from which the marginal portions of the article wrapper extend, an adhesive supply roller, a rotative adhesive-applying member mounted adjacent said article-holding member and having a radial blade adapted to travel to and from its adhesive-applying position edgewise the path of the extended portions of said wrappers, and an oscillating member adapted to press the extended portions of the wrappers in into contact with said blade in its applying position. 115

6. In an adhesive-applying device, the combination of a rotative drum having article-holding pockets from which the mar- 120

ginal portions of the article wrappers extend, an adhesive supply roller, a rotative transfer member mounted intermediate said drum and said supply roller and having a radial blade 5 adapted to travel from a position in edge-wise contact with said supply roller to an adhesive-applying position in the path of the extended portions of said wrappers, a presser bar located in the path of the margins of 10 the wrappers, and means for oscillating said presser bar to bring said margins of the wrappers into contact with said blade in its adhesive-applying position.

Signed at Chicago, Ill., this 30th day of 15 Jan., 1929.

WILLIAM LINDSEY.
